UNITED STATES PATENT OFFICE

MAURICE EYQUEM, OF PARIS, FRANCE

SPARK PLUG

Application filed February 3, 1928, Serial No. 251,860, and in Belgium February 8, 1927.

The present invention relates to spark-plugs.

One of the objects of the invention is to provide an improved form of seal which will prevent any possibility of leakage.

Another object is to improve the insulating material and the manner of applying the same so that the various conductors are properly insulated throughout the range of ordinary operating temperatures.

Still further objects will appear in the course of the detailed description which will now be given with reference to the accompanying drawings, in which:

15 Fig. 1 is a longitudinal section through one constructive embodiment of the invention;

Fig. 2 illustrates, in section, another modification of the invention;

20 Fig. 3 shows still another form of plug constructed in accordance with the invention.

Referring to the drawings, there is shown a central cylindrical conductor *b* terminating at one extremity in an enlarged portion *b*¹ and an electrode *e* and at its other extremity in a threaded portion engaging with terminal block *c* adapted to be supplied with current from cable terminal *d*—a series of insulating mica sheets *f* maintained in place on *b* by a sheath of paper or other flexible material *f*¹ glued or otherwise adhesively attached to the longitudinal free edge of sheets *f*—an outer casing *a* having a threaded portion *a*¹ adapted to engage in the cylinder head—a copper washer *o* seated on a shoulder *a*² formed inside of casing *a*—a stack of mica washers *g* in the form of a truncated cone resting on *b*¹ and slightly spaced

35 from sheath *f*¹ and washer *o*—a cylindrical sleeve *h* in threaded engagement with casing *a* and adapted to hold washers *g* and *o* firmly in position—a pair of annular washers *j* and *i* of trapezoidal section sliding

40 over *f*¹ with slight play and containing between them a layer of finely pulverized insulating material *k* formed of steatite, quartz or the like—a pressure member *l* in threaded engagement with *h* and adapted to act on washers *j* and *i* so as to force powder *k*

centrifugally against *f*¹ and thus effectively seal the device:—and a stack of mica washers *p* interposed between *l* and *c*.

The modification shown in Fig. 2 differs from that illustrated in Fig. 1 mainly in the form of the washers used for compressing powder *k*. Here washer *i* of Fig. 1 is replaced by a member *m* resting directly on an internal shoulder of casing *a* and having its upper extremities turned over in contact with washer *j*. Pressure member *l* of Fig. 1 is eliminated, the turned over edges of *m* functioning to press washer *j* down onto powder *k*. The device differs otherwise only in the positioning of copper washer *o* which is here interposed between a shoulder on member *m* and the end of sleeve *h*.

The device shown in Fig. 3 differs again only in details from that represented in Fig. 1. In this modification mica washers *g* and *p* Figs. 1 and 2 are replaced by porcelain, pyrex, or quartz elements *p*¹ and *f*², the latter having a central bore adapted to fit very closely over the uninsulated portion of central conductor *b* and with slight play over insulated portion *f*. *f*² is held firmly in place against copper washer *e*¹ by sleeve *h* and serves as direct support for powder *k*. Only one wedge shaped washer *j* is used in this form of assembly, pressure being applied thereto by the overturned edge of sleeve *h*.

From the foregoing, it will be seen that in each modification means are provided for forcing an insulating powder by a sort of wedging action into firm contact with the only joint which is liable to leakage. It is to be understood that the invention is not to be taken as limited to the particular structures described. Thus, the mica insulating sheets enclosing conductor *b* may be replaced by a sheath of varnish, enamel, or an insulating resin formed of a phenol condensation product; the mechanical details shown in Fig. 1 such as pressure member *l* may be transposed to the devices shown in Figs. 2 and 3; an assembly involving the use of member *m*, Fig. 2, may be used in connection with the structures shown in Figs. 1 and 3; etc.

What I claim is:—

1. In a spark-plug, a sealing assembly including a conductor, a sheet of mica enclosing said conductor, and a flexible material continuously covering the free longitudinal edge of said mica sheet.
2. In a spark-plug, a sealing assembly including a conductor, a sheet of mica partially enclosing said conductor adapted to insulate the latter, and a pulverized insulating material packed against said mica sheet.
3. In a spark-plug, a sealing assembly including a conductor, a sheet of mica partially enclosing said conductor, a flexible material continuously covering the free longitudinal edge of the mica sheet, and a pulverized insulating material packed around said flexible material.
- 20 4. A spark-plug as defined in claim 2 in combination with means for forcing the pulverized insulating material centripetally against the mica sheet.
- 25 5. A spark-plug as defined in claim 3 in combination with means for forcing the pulverized insulating material centripetally against the mica sheet.

In testimony whereof I have hereunto set my hand.

MAURICE EYQUEM.
